(57) **CLAIM**

The ornamental design for a photobiomodulation therapy device, as shown and described.

DESCRIPTION

FIG. 1 is a top, front, right perspective view of a photobiomodulation therapy device embodying the new design; FIG. 2 is a top, rear, left perspective view thereof; FIG. 3 is a bottom, rear, right perspective view thereof; FIG. 4 is a front elevation view thereof; FIG. 5 is a rear elevation view thereof; FIG. 6 is a right side elevation view thereof; FIG. 7 is a left side elevation view thereof; FIG. 8 is a top plan view thereof; and, FIG. 9 is a bottom plan view thereof.

In the drawings, the equal-length broken lines depict portions of the photobiomodulation therapy device that form no part of the claimed design. The dash-dot-dash broken lines define the boundaries of the claim. All broken lines form no part of the claimed design.
